WINDOW CONSTRUCTION AND METHOD OF
INSTALLING THE SAME

Benjamin J. Triller, Dubuque, Iowa

Application April 1, 1937, Serial No. 134,392

11 Claims. (Cl. 20—52.2)

The object of this invention is to provide a window construction and method of installing the same, whereby the window may be fitted and weatherstripped at the factory and shipped in knock-down form and assembled in a novel manner on the job.

A further object is to provide a structure and method whereby the sash may be readily removed and replaced after once being installed in a building.

With the above and other equally important objects in view as will occur as the description progresses, reference will be had to the accompanying drawings forming a part of this specification and wherein:

Fig. 1 is a conventional sectional view showing of the head, jamb and sill portions of the window frames and sash installed in a building, the head and sill portions being shown in vertical section and a jamb portion being shown in horizontal section,

Fig. 2 is an enlarged horizontal sectional view of one side jamb and a fragment of the sash,

Fig. 3 is a vertical sectional view taken through the meeting rail portions of the sash showing the rails in different positions and the relative location of the plowed recess,

Fig. 4 is a similar view with the lower sash raised,

Fig. 5 is a diagrammatic perspective view of one side of the inner frame showing a parting stop section being inserted,

Fig. 6 is an enlarged sectional view taken through the central portion of a side jamb showing the relation of the plowed recess to the raised lower sash, and the method of applying the parting stop sections,

Fig. 7 is an enlarged horizontal sectional view taken through a fragment of a side jamb, parting stop and upper and lower sash,

Fig. 8 is an assembly view of the outer frame incorporated in a wall and showing the inner frame in juxtaposed position for assembly,

Figs. 9 and 10 are fragmentary detail views in elevation showing the method of applying the sash balances before closing the head opening in the inner frame,

Fig. 11 is a similar view showing the method of applying and removing the upper parting stop sections in connection with the removal and insertion of the sash after the frame has been incorporated in the building.

Fig. 12 is a plan view of a fragment of a bundle of sash,

Fig. 13 is an end view of a fragment of a bundle of side jambs, and

Fig. 14 is an end view of a fragment of a bundle of heads and sills.

In the drawings, reference numeral 1 designates the head, 2 the jambs, and 3 the sill of an inner window frame section. A parting stop 4 is provided in the head, and parting stop 5 is also provided in the side jambs, these being set into grooves 6 in the conventional manner. 10 Upper and lower sash 7 and 8, respectively, are mounted in the inner window frame section at opposite sides of the parting stops, being previously fitted and weatherstripped at the factory. In shipping, several pairs of jambs will be packed 15 separately as in Fig. 13, several pairs of heads and sills will be packed separately as in Fig. 14, and several pairs of sash will be bundled as in Fig. 12 or all parts for one or more complete windows may be packed in the same bundle. 20

In erecting the building, the outer frame parts 10, 11 and 12, constituting the head, jambs and sill respectively of an outer frame are installed initially in the wall of the building around the window opening as illustrated in Fig. 8, in accordance with the general idea of Patent 1,995,-233 and thereafter at a later stage in the construction of the building, the inner frame parts 1 to 8 inclusive are assembled and installed, and the final trim 14, 15 and 16 applied according to the method set forth in said patent, the outer frame parts 10 and 11 and the trim parts 14, 15 and 16 providing outer stops for the sash. 25

The side portions of the side parting stops 5 (Fig. 7) that project from the grooves in the side jambs are rabbeted at 17, and the inner corners of the sash 7 and 8 are also rabbeted as at 18. Weather strippings are applied to the parting stops and sash and located almost entirely within the rabbets thereof. 35

The jamb weather-stripping consists of a metal strip bent longitudinally to provide a central bridge portion 20, right-angular parallel sides 21, right-angular aligned portions 22 parallel to the plane of the portion 20, and right-angular free side portions 24 parallel to the sides 21. The portion 22 is applied to the exposed face of the parting strips 5, the portions 21 are applied to the sides of the parting strips 5, the portions 22 are applied to the bottoms of the rabbets 17 in the plane of the inner face of the side jambs 2, and the portions 24 extend parallel with the portions 21 and form therewith and with the portions 22 a U-shaped channel A opening away from the side jamb. 40

The weather stripping for the sash each consists of a metal strip longitudinally bent to form lip 25 by which it is secured to the jamb side of the sash, a right-angular portion 26 that hugs the side of the rabbet 18, a right-angular portion 27 that parallels the plane of the portion 25 and that hugs the base of the rabbet 18, and a right-angular free side portion 28 that extends parallel to portion 26 in the direction of the jamb, and forms with said portions 26 and 27 a channel B opening toward the side jamb. The bridge portion 20 and lips 25 are not countersunk.

After the building is plastered and dried and preferably after other rough work that could cause damage to sash runways has been completed, the bundled inner frame parts are delivered to the building. The two jambs 2 with their parting stops 5 and weatherstripping, factory applied, are then nailed to the sill 3. Both sash, 7 and 8, factory fitted, are then slid in from the top in proper interlocked engagement with the weatherstripping. The sash balancing springs 30 are now, or were previously nailed at their upper ends 31 to the upper portion of the side jambs 2, their lower ends being arranged between the jambs and sash in conventional grooves therefor. The lower ends of the springs are equipped with plates 32 by means of which the springs may be wound to shorten and to place the desired tension upon the spring, whereupon, the plates 32 are nailed at 33 to the lower edge of the sash. The head 4 with its parting strip 4 and weatherstripping is then nailed to the upper ends of the side jambs, as shown in Fig. 11, thereby completing the inner frame assembly. Obviously, all the parts may be painted or varnished before the parts are assembled.

Since all fitting and weatherstripping was done at the factory, the assembled sash may now be operated as freely as after the inner frame unit is attached to the outer frame unit already in the wall.

In split frame construction according to said patent, the inner frame unit has no other stops than the parting stops or strip 4 and 5, that is to say, there are no customary outer stops. The inner frame unit with the sash in place may, nevertheless, be moved about without danger of the sash falling out since the interlocking weatherstripping holds the sash in place without outer stops being present. This is a very desirable feature since it not only offers the added advantages of interlocking weatherstripping but also permits the inner unit parts to be shipped knock-down making it unnecessary to ship the inner unit completely assembled as in the said patent.

After the inner frame unit has been incorporated in the building, the sash cannot be removed by merely reversing the steps employed in the original assembly of the frame, for obvious reasons, and other means must be provided for the removal and reincorporation of the sash. To permit this, the parting strips 5 on both sides of the window are divided into upper and lower sections, the joint C between the sections occurring at a point substantially midway between the upper and lower faces of the meeting rails of the sash when closed as shown in Fig. 3. In addition, there is provided a plowed recess 35 in each side jamb 2. The recess is in effect a deepening of the groove 6 of the side jamb in which the parting strips are seated, and does not extend entirely through the jamb.

To remove the sash, the same are raised to their limit, with the meeting rails in the Fig. 4 position, and the screws 36 are then removed from the lower sections of the parting strips 5, and the lower ends thereof pulled out of the groove 6 as shown in Fig. 5. Since, as seen in Figs. 4 and 6, the bottom rail of the lower sash, when both sash are raised, is below the lower or meeting rail of the top sash, and the lower edges of the said rails are both below the joint C 10 between the parting strip sections, it would be impossible to swing the lower ends of the lower sections 5 of the parting strip inwardly were it not for the presence of the plowed recess 35 permitting said strip sections to fulcrum on the 15 lower corners of the bottom rail of the raised lower sash, as shown in Fig. 6, in which view the reference letter D designates the position of the lower edge of the raised upper sash which, for clarity, has been removed. As the lower section 20 of parting strips on both sides of the window fulcrum upon the corner of the raised lower sash, their upper ends swing away from both sash, this being the direction of movement necessary to disengage the weatherstripping of the parting 25 strips from the weatherstripping of the sash. When in the positions shown in Figs. 5 and 6, the parting strip sections are pulled longitudinally downward into completely disassembled position.

One sash is then, if not previously, lowered to permit removal of the screws 36 of the upper sections of the parting strips 5. These sections are then slid downwardly in their grooves 6, and upon raising the sash to their full elevated positions, these upper parting strip sections may be slid entirely down to the permitted limit of movement and may then be removed in the same manner as the lower parting strip sections. This frees both sash except for the sash balancing 40 springs which may be readily released when the sash are moved to a position permitting removal of the nails 31 or 32, as elected.

Obviously, by reversing the operation, the sash may be reassembled as in the original installation.

What is claimed is:—

1. The method of constructing and installing windows, consisting in installing an outer frame unit in an opening in a building wall, providing 50 an inner frame unit with parting stops, slidably confining prefitted sash in said inner frame unit by interlocking weatherstripping between the sash and parting stop, and finally applying the inner frame unit with its incorporated sash to 55 said outer frame unit.

2. The method of constructing and installing windows, consisting in installing an outer frame unit in an opening in a building wall, constructing 60 an inner frame unit by securing a cross member to corresponding end portions of jambs which are initially provided with weatherstripping, then sliding sash which are initially provided with weatherstripping into the inner frame unit from the open end thereof meanwhile interlocking the jamb and sash weatherstripping to confine the sash in the inner frame unit, closing the open end of the inner frame unit by a second cross member, and finally in applying the inner frame with its incorporated sash to said 65 outer frame unit.

3. The method of constructing and installing windows, consisting in installing an outer frame unit in an opening in a building wall, constructing 70 an inner frame unit by securing a sill to cor- 75

responding end portions of jambs which are initially provided with parting stops having weatherstripping, then sliding sash which are initially provided with weatherstripping into the inner frame unit from the open end thereof meanwhile interlocking the jamb and parting stop weatherstripping to confine the sash in the inner frame unit, closing the open end of the inner frame unit by a head member, and finally in applying the inner frame with its incorporated sash to said outer frame unit.

4. The method of constructing and installing windows, consisting in installing an outer frame unit in an opening in a building wall, constructing an inner frame unit by securing a sill to corresponding end portions of jambs which latter are initially provided with removable sectional parting stops having sectional weatherstripping, then sliding sash which are initially provided with weatherstripping into the inner frame unit from the open end thereof meanwhile interlocking the jamb and parting stop weatherstripping to confine the sash in the inner frame unit, closing the open end of the inner frame unit by a head member, and finally in applying the inner frame with its incorporated sash to said outer frame unit.

5. The method of constructing and installing windows, consisting in installing an outer frame unit in an opening in a building wall, constructing an inner frame unit by securing a sill to corresponding end portions of jambs which latter are initially provided with removable sectional parting stops having sectional weatherstripping, then sliding sash which are initially provided with weatherstripping into the inner frame unit from the open end thereof meanwhile interlocking the sash and parting stop weatherstripping to confine the sash in the inner frame unit, securing upper ends of sash balancing coil springs to the jambs, winding the springs to place them under tension, securing the lower ends of the springs to the sash, closing the open end of the inner frame unit by a head member, and finally in applying the inner frame with its incorporated sash to said outer frame unit.

6. A window frame provided with side parting stops and a removable end bar, upper and lower sash arranged within said frame on opposite sides of said parting stops, weatherstripping on the parting stops slidably interlocking with the weatherstripping on the sash and serving to confine the sash in the frame, said sash being insertable into said frame when said end bar is removed.

7. A window frame provided with jamb parting stops upper and lower sash arranged within said frame on opposite sides of said parting stops, weatherstripping on the parting stops simultaneously slidably interlocking with the weatherstripping on the sash and serving to confine the sash in the frame, said parting stops and their weatherstripping being in sections, upper and lower removable sections abutting each other approximately at the center line of the meeting rails of the sash, and means permitting removal of the parting stops and sash from the frame after the window is installed.

8. A window frame provided with jamb parting stops, upper and lower sash arranged within said frame on opposite sides of said parting stops, weatherstripping on the parting stops simultaneously slidably interlocking with the weatherstripping on the sash in the frame, said parting stops and their weatherstripping being in sections, upper and lower removable sections abutting each other approximately at the center line of the meeting rails of the sash, the parting stops being slidably and removably arranged in grooves in the jambs of the frame, the groove being deepened adjacent the center lines of the meeting rails of the sash and continuing on each side of said center line to provide space for the pivoting movement of the weatherstripped parting stop sections during removal thereof.

9. In a structure of the character described, a building wall provided with an outer window frame, an inner window frame in the wall, coinciding with the outer window frame, trim coinciding with the inner frame, said inner frame comprising a head bar, sill and jambs detachably connected together, said jambs being provided with grooves extending substantially throughout the height of the inner frame, each groove being of greater depth at its medial portion than at its other portions, an upper and lower parting stop extending into each groove and having adjacent ends arranged where the deepened portion of the groove is located, each parting stop being detachably connected to a jamb of the inner frame, metallic weatherstrips secured to the parting stops, upper and lower sash arranged within the inner frame on opposite sides of said parting stops, and weatherstrips on said sash interlocked with the weatherstrips of the parting stops to form guides for the sash, the deepened portions of the grooves permitting all of the parting stops to be removed when the sash are in certain positions.

10. A window frame provided with jamb parting stops, upper and lower sash arranged within said frame on opposite sides of said parting stops, interlocked weatherstripping on the parting stops and sash serving to confine the sash in the window frame, said parting stops and their weatherstripping being in upper and lower removable sections having adjacent ends arranged approximately at the center line of the meeting rails of the sash, and means permitting removal of the parting stops and their weatherstripping from the frame after the window is installed, to allow removal of the sash.

11. A window frame provided with jamb parting stops, upper and lower sash arranged within said frame on opposite sides of said parting stops, weatherstripping on the parting stops having grooved portions at opposite sides thereof, weatherstripping on the sash having grooved portions slidably interlocked with the grooved portions of the weatherstripping on the parting stops whereby the weatherstripping serves to confine the sash in the frame, said parting stops being removable from the frame separately from the sash to facilitate removal of the sash after the window is installed.

BENJAMIN J. TRILLER.
